VACUUM VALVE

Charles B. Petry, Fair Lawn, N. J., assignor to
 'Allen B. Du Mont Laboratories, Inc., Passaic,
 N. J., a corporation of Delaware

Application March 9, 1944, Serial No. 525,799

7 Claims. (Cl. 137—78)

1

This invention relates to a valve that is particularly useful in connection with means for exhausting the air from tubes in making vacuum tubes. In carrying out the invention the valve is so arranged that it can be electrically operated in a very simple and rapid manner.

The invention may be understood from the description in connection with the accompanying drawing in which reference character 1 indicates a manifold which is provided with a series of tubular projections 2 which are adapted to have glass bulbs or tubes or the like hermetically sealed thereto so as to permit passage of air from such bulbs into the manifold 1 when a vacuum is applied to this manifold.

The manifold 1 is connected to a container 3 and a pipe 4 connects this container to a vacuum tank 5 that is connected by pipe 6 to vacuum pump 7.

A Sylphon 8 has its lower end 9 attached to the top side of container 3 so as to be hermetically sealed thereto. The upper end 10 of this Sylphon is similarly attached to a closure member or disc 11 to which it is hermetically sealed. This disc 11 is provided with a stem 12 extending loosely through an opening 13 in the container 3 and terminates in a valve 14. A seat 15 of rubber or similar material is provided for the valve 14.

A compression spring 16 surrounds the Sylphon 8 and has its outer end bearing against the member 11 and its lower end resting upon the upper side of a large nut 19 that is adjustably mounted upon a hollow externally threaded member 20 that is attached to the top side of the container 3.

21, 21' and 22, 22' are pairs of solenoids fixed in position in any convenient way, not shown, with respect to the member 11. The movable cores or plungers 23, 23' of solenoids 21, 21' are provided with downwardly and outwardly sloping ends 24, 24'. The movable cores or plungers 25, 25' of solenoids 22, 22' are provided with downwardly and inwardly sloping ends 26, 26'. The plungers 23, 23' and 25, 25' are biased in any convenient way, as for example, by springs 27, 27' to remain normally in the position shown in the drawing but are adapted to be retracted outwardly by the solenoids 21, 21' and 22, 22', respectively. The operation is as follows:

With the parts in the positions shown in the drawing the tubular projections 2 which may be of glass on manifold 1 are closed at their upper or outer ends and the outer end of this manifold 1 is also closed. The pump 7 is started and when

2

sufficient vacuum obtains in container 3 the solenoids 21, 21' are energized thus retracting the solenoid cores 23, 23' and permitting the valve 14 to close upon the rubber valve seat 15 due to gravity and the vacuum created in the Sylphon 8. At the same time the edge of the circular top portion 11 passes across the sloping ends 26, 26' of plungers 25, 25' whereupon the plungers snap back into place and catch over the upper surface of member 11 as shown in the dashed line position 11'.

The ends of the tubular projections 2 are then opened and the glass vessels such as blanks for vacuum tubes, etc. are sealed in place on these tubular projections so that a vacuum in container 3 will remove the air from them when communication to this container is established. The opening of the tubular projections 2 for this purpose removes the vacuum from container 3, thus establishing atmospheric pressure therein while the valve 14 which is latched in place by solenoids 25, 25' on seal 15 maintains the vacuum in tank 5.

The solenoids 22, 22' are then energized, thus retracting the plungers 25, 25' and permitting the spring 16 to return the valve 14 to the position shown in solid lines on the drawing with the portion 11 held in the outer position by the plungers 23, 23' which snap back under the lower side of the circular top portion 11 after its edge has passed across the sloping surfaces 24, 24'.

The position to which the nut 19 is adjusted on threaded member 20 is such that the spring 16 is compressed sufficiently to lift the valve member 14 from the seat 15 against the air pressure in container 3 when there is no vacuum in the manifold 1 and chamber 3. The top area of the Sylphon 8 is such that atmospheric pressure on the outside thereof is sufficient to close the valve 14 on valve seat 15 when the solenoids 23, 23' are retracted and vacuum exists in the container 3.

45 What is claimed is:

1. A device for exhausting air from glass tubes, which comprises a container, tubes communicating with said container, a vacuum tank with which one of said communicating tubes communicates, a valve seat in said container at the end of said last mentioned communicating tube, said other tube being closed at its outer end and having a sealable outlet along the side thereof, a valve for said seat, a stem for said valve, a Sylphon around said stem having one end there-

of bearing against the outside of said container and secured thereto, a disc hermetically sealed to the other end of said Sylphon and connected to the stem of said valve and an expansion spring surrounding said Sylphon having one end thereof bearing against said disc and the other end bearing against a nut on a threaded member that is attached to said container.

2. The device of claim 1 in which a catch for said disc is provided outside of said container to hold it in its outer position.

3. The device of claim 1 in which a catch for said disc is provided outside of said container to hold it in its inner position.

4. The device of claim 1 in which an electrically operated catch for said disc is provided outside of said container to hold it in its outer position.

5. The device of claim 1 in which catches are provided outside of said container to hold said disc in two different positions, one of which is that in which said valve is on its seat.

6. The device of claim 1 in which electrically operated catches are provided outside of said

5

container to hold said disc in two different positions, one of which is that in which said valve is on its seat.

7. The device of claim 1 in which an adjustable member is provided between one end of said expansion spring and said container.
